UNITED STATES PATENT OFFICE.

FRANK BEIDELSTEIN, OF MILWAUKEE, WISCONSIN.

DESIGN FOR A GAME-WHEEL SPIDER.

Application filed July 18, 1925. Serial No. 14,137. Term of patent 3½ years.

To all whom it may concern:

Be it known that I, FRANK BEIDELSTEIN, a citizen of the United States, residing at Milwaukee, in the county of Milwaukee and State of Wisconsin, have invented a new, original, and ornamental Design for a Game-Wheel Spider, of which the following is a specification, reference being had to the accompanying drawing, forming a part thereof.

The figure is perspective view of a game wheel spider, showing my new design.

I claim:

The ornamental design for a game wheel spider substantially as shown.

In testimony whereof, I affix my signature at 123 Grand Ave. Milwaukee, Wisconsin.
